The ornamental design for a hood with a face mask, as shown and described.

DESCRIPTION

FIG. 1 is a perspective view of the hood and face mask of the present design positioned on a body;

FIG. 2 is a perspective view thereof with the face mask in an alternate position on the body;

FIG. 3 is a perspective view thereof positioned on a helmet disposed on the body;

FIG. 4 is a left side elevational view thereof as positioned on the body in FIG. 1;

FIG. 5 is a right side elevational view thereof as positioned on the body in FIG. 1;

FIG. 6 is a front elevational view thereof as positioned on the body in FIG. 1;

FIG. 7 is a rear elevational view thereof as positioned on the body in FIG. 1;
FIG. 8 is a top plan view thereof as positioned on the body in FIG. 1;
FIG. 9 is a bottom plan view thereof as positioned on the body in FIG. 1;
FIG. 10 is a perspective view of the hood and face mask of the present design positioned on a body, according to a second embodiment of the design;
FIG. 11 is a perspective view according to the second embodiment of the design with the face mask positioned in an alternative position on the body;
FIG. 12 is a perspective view according to the second embodiment of the design positioned on a helmet disposed on the body;
FIG. 13 is a left side elevational view according to the second embodiment of the design as positioned on the body in FIG. 10;
FIG. 14 is a right side elevational view according to the second embodiment of the design as positioned on the body in FIG. 10;

FIG. 15 is a front elevational view according to the second embodiment of the design as positioned on the body in FIG. 10;

FIG. 16 is a rear elevational view according to the second embodiment of the design as positioned on the body in FIG. 10;

FIG. 17 is a top plan view according to the second embodiment of the design as positioned on the body in FIG. 10; and, FIG. 18 is a bottom plan view according to the second embodiment of the design as positioned on the body in FIG. 10.

The broken lines shown within the hood in FIGS. 10-18 represent stitching that is part of the claimed design. The broken lines showing the body and helmet on which the hood with face mask is positioned and showing the end of the pull ties extending from the hood in FIGS. 1-18 are for the purpose of illustrating portions of the environmental structure and form no part of the claimed design.
